UNITED STATES PATENT OFFICE.

WILLIAM B. SAVELL, OF NEWARK, NEW JERSEY.

TYPE-WRITER OR ANALOGOUS KEY CAP.

SPECIFICATION forming part of Letters Patent No. 705,709, dated July 29, 1902.

Application filed February 17, 1902. Serial No. 94,466. (No model.)

To all whom it may concern:

Be it known that I, WILLIAM B. SAVELL, a citizen of the United States, residing at Newark, in the county of Essex and State of New Jersey, have invented new and useful Improvements in Type-Writer and Analogous Key Caps, of which the following is a specification.

This invention relates to certain new and useful improvements in caps adapted to be fitted to the keys of type-writing machines, cash-registers, and other manually-operated machines on which keys are to be employed which are to be rapidly and often struck by the fingers.

The objects of the invention are essentially to relieve the fingers of the operator from soreness caused by striking the unyielding surface of the keys commonly used on the machines above noted, and, second, to provide a key-cap (whether cushion or otherwise) which is reversible or capable of having its position so altered on the key as to show either a lettered surface or a blank surface—*i. e.*, one devoid of letter or other designating character.

A further object is to provide opposite surfaces of the touch member of a key-cap with letters or symbols of different kind or character, so that when reversed a different keyboard is shown.

The invention consists, essentially, of a touch surface or member to be fitted to and supported above the top of the keys and capable of having its position reversed or changed to present either side uppermost for use as an operating-surface.

It also consists of a removable and reversible touch surface or member supported above the top of the key and having one face provided with a designating letter or symbol and an opposite or reverse face provided with a different character or symbol.

It further consists of a reversible touch surface or member supported above the top of the key and having one face provided with a designating letter or symbol and an opposite or reverse face provided with a different character or symbol.

It also consists of a key-cap having a yielding or cushioned touch surface or member supported above the top of the key when in

use, said surface or member being capable of reversal to present either face uppermost and one of said surfaces being marked alike or different from the other.

Finally, it consists of the parts and the constructions and combinations of parts which I will hereinafter describe and claim.

In the accompanying drawings, forming part of my invention, and in which similar letters of reference indicate like parts throughout the several views, Figure 1 is a perspective view of a key-cap embodying my invention. Fig. 2 is a vertical sectional view of the same. Fig. 3 shows the touch member of Figs. 1 and 2 removed and reversed and devoid of character or symbol. Fig. 4 is a sectional perspective view showing a cap of slightly-modified form. Fig. 5 represents the touch member of Fig. 4 removed and reversed to show a different character on its reverse side. Fig. 6 is a sectional view similar to Fig. 2 and showing the invention applied to the ordinary key of a Remington type-writing machine. Fig. 7 shows the application of the reversible touch member directly to a key-head.

Referring to the aforesaid drawings, A represents the ordinary key of a type-writing or similar manually-operated machine employing a keyboard made up of any desired number of said keys, each of which keys usually has a letter or other character that identifies the key with the type on the type-bar, which is connected with the key in the usual or any desired manner.

To the key A is fitted a cap which comprises a band or rim B of metal, celluloid, or other desired and appropriate material, which is designed to fit over the key A, said band or rim having an upper edge or flange *a* turned inward to appropriately engage the touch member C. This touch member is of a soft yielding character and may be composed of rubber, felt, or other desired material, and it has a circumferential groove *b*, which is detachably engaged by the aforesaid inturned edge or flange *a* of the band or rim. Inlaid or otherwise secured in or to the face of the touch member C is a letter or symbol D of a color which contrasts from that of the body of the material of which the touch member is composed. As far as described, except for

- the circumferential groove and the detachability of the touch-surface, the rim or band and the touch member, with its letter or symbol, are not essentially different from what 5 is disclosed in my former patents, No. 504,065, August 29, 1893; No. 532,153, January 8, 1895; No. 551,543, December 17, 1895; Nos. 563,163 and 563,164, June 30, 1896, and No. 569,196, October 13, 1896.
- 10 In the present instance an essential purpose is to make the touch member removable and reversible with letters or symbols alike or unlike on one or both sides. In other words, the present invention contemplates, 15 broadly, a key-cap or touch member, whether of cushion form or otherwise, which may be reversed or so changed as to show either a blank or a lettered surface or two surfaces lettered alike or unlike.
- 20 In Figs. 1, 2, and 3 the touch member C has a letter in or on one surface 2, the opposite surface 3 being blank, and its circumferential groove is so engaged by the inturned edge or flange of the band or rim that a bending or compression of the touch member (the band being removed from the key) will detach the said member, which when reversed, 25 may be again sprung into proper engagement with the band, with the edge or flange a of the latter engaging the groove of the former.
- 30 The key A of Fig. 1 has the usual concaved surface d, and supported around the edge of this key is a ring e, which may be of either hard 35 or soft material and whose function is to support the touch member or cushion a suitable distance above the key to provide the space for the cushion effect. This ring e is not always essential, as in some instances the de- 40 pressed center of the key affords enough space to obtain the desired cushion effect. The same result is also produced when using the form of touch member shown in Fig. 4, where the equivalent of the ring is to be found in the bead or flange e', which is molded or 45 otherwise made a part of the touch member. In said Fig. 4 both surfaces of the touch member are provided with letters or symbols, and either surface may be used uppermost.
- 50 In Fig. 6 I show the invention applied to the Remington key, where the usual cardboard and glass disks have been removed and my cushioned cap applied, and in Fig. 7 I illustrate the application of my flexible touch member directly to and forming the touch-surface 55 of another form of key. In these figures (6 and 7) the cardboard and glass disks usually employed are omitted, and their place is taken by the reversible touch member, which is 60 supplied with the character usually carried by the said cardboard disk, said touch member being put directly on and supported above the top of the key and being not only a substitute for the said disks, but also a cushion, 65 as before described.

The key shown in Fig. 6 is formed with an inturned flange at the top, which serves for

our band B, and the thickness of the block or touch member relative to the height of the said flange above the top of the key proper 70 is such that the bottom of the touch member is held above the top of the key.

The cap or touch member hereinbefore described possesses the cushioned effect of my prior patented devices, and from its use flow 75 certain additional advantages, among which may be enumerated the following:

(a) It is simpler and more cheaply manufactured than the cushion-key heretofore devised. 80

(b) The cushion or yielding touch portion can be more easily removed when worn and replaced with a new one.

(c) The touch member can be reversed to show a blank surface, the shape and appearance otherwise remaining exactly the same. 85 This is a most useful feature where operators desire to become accustomed to writing without seeing the characters on the keys. The operator can reverse one or two keys at first 90 and later one or two more, continuing this process until the whole keyboard is thus gradually made blank.

(d) The touch member can be made with a character on each side of the same kind, so 95 that should one character become obscured or obliterated a reversal of the member brings a new character to view.

(e) The touch member can be made with different characters on each side, so that 100 when reversed a different keyboard is shown. This is particularly useful for type-writers which have changeable type for writing different languages and overcomes one of the most annoying features which these type-writer companies have had to contend with in connection with the changing of type, as very rarely does the same keyboard suit more than one language. Again by marking one side of two touch members with a letter or a character frequently used in writing and the other sides with a character little used (for instance, the E and Z) these members can be exchanged when one becomes worn and the one most worn replaced by the other. In this way the 110 set of caps can be made to last nearly twice as long as it otherwise would. 115

Having thus described my invention, what I claim as new, and desire to secure by Letters Patent, is—

1. A key-cap having a reversible touch member supported above the top of the key when in use.
2. A key-cap having a reversible touch member supported above the top of the key 125 when in use said touch member capable of reversal to bring either side uppermost, and provided with a designating symbol.
3. A key-cap having a touch member supported above the top of the key when in use 130 said member capable of reversal to bring either side uppermost and both of said sides having a designating character.
4. A key-cap having a reversible touch

member supported above the key when in use and having a designating character in each side, one of said characters being different from the other.

5. In a device of the character described, the combination of a member, as a rim or band, a reversible touch member of yielding material, one of said members having a peripheral groove and the other member having 10 a projection or flange to detachably engage

said groove, and means for elevating the under side of the touch member above the top surface of the key.

In testimony whereof I have hereunto set my hand in presence of two subscribing witnesses. 15

WILLIAM B. SAVELL.
